CHRISTMAS TREE STAND

Fred H. Tiff, 372 Moore Ave.,
Yuba City, Calif. 95991

Filed Oct. 7, 1968, Ser. No. 13,853

Term of patent 14 years

Int. Cl. D6—01

U.S. Cl. D35—3

FIG. 1

FIG. 2

FIG. 3

FIG. 4

FIGURE 1 is a perspective view of a Christmas tree stand showing my new design;

FIGURE 2 is a top plan view;

FIGURE 3 is a bottom plan view; and

FIGURE 4 is an enlarged fragmentary view, partially shown in cross-section, and taken on line 4—4 of FIGURE 2, with one of the support members omitted for ease of illustration.

I claim:

The ornamental design for a Christmas tree stand, as shown and described.
